UNITED STATES PATENT OFFICE

2,120,292

VENETIAN BLIND

Julius Nisenson, Brooklyn, N. Y., assignor to
Master Venetian Blind Hardware Corporation,
New York, N. Y., a corporation of New York

Original application May 1, 1935, Serial No.
19,184. Divided and this application November
26, 1935, Serial No. 51,637

11 Claims. (CL. 156—17)

This invention relates generally to improvement in window blinds of a class known as Venetian blinds, and more particularly to improvements in the head-bar and bracket supporting means therefor.

The present application constitutes a division of an application filed May 1, 1935, bearing Serial No. 19,184, issued as Patent No. 2,072,464, March 2, 1937.

10 This invention has for an object the provision of structure wherein the head-piece or casing thereof may be simply and conveniently adjusted longitudinally to properly fit window casements of different widths.

15 Heretofore, in Venetian blinds the mechanism for raising or tilting the slats has been exposed, and could not be conveniently removed for cleaning purposes. It is a further object of this invention to provide a Venetian blind in which all 20 of the operating mechanism is concealed from view in a casing, and yet provide means for readily detaching the casing from supporting brackets so that the mechanism can be easily cleaned and oiled when necessary.

25 Another object of the present structure is to provide an arrangement of pulleys with relation to the operating mechanism whereby the operation thereof is unaffected when the casing is longitudinally adjusted.

30 This invention presents a Venetian blind head-piece and bracket construction which is mechanically durable and substantial, yet light in weight, extremely compact and inconspicuous, neat and good looking, readily removed from the 35 supporting brackets or replaced thereon in a simple manner by anyone having no particular skill.

35 A further object of this invention is the provision of structure whereby the control or operating cords of the blind operating mechanism are maintained at a predetermined distance from the vertical frame members of the window casement regardless of the horizontal longitudinal adjustment of the head-piece.

40 Another advantage of the present invention lies in the fact that the head-piece structure and brackets therefor may be utilized with Venetian blind assemblies having various types of slat tilting and elevating mechanisms.

45 A still further advantage of the present construction resides in the simplicity in manufacture and assembly, together with the adaptability of the parts wherein slight changes in assembly 50 permit blinds of extreme variations in width to

be constructed with consequent reduction in manufacturing costs.

These objects and further features, incidental ends and advantages will more fully appear in the progress of this disclosure and as pointed out in 5 the appended claims.

In the accompanying drawing, similar reference characters designate corresponding parts throughout the several views in which:

Figure 1 is a fragmentary elevational view 10 showing a Venetian blind embodying the present invention.

Figure 2 is an end view in elevation of a casing or head-piece of a Venetian blind supported on a bracket, as embodied in the present invention. 15

Figure 3 is a plan view of the head-piece partly broken away as supported on the brackets therefor.

Figure 4 is a vertical sectional view of Figure 3 taken along the plane 4—4 thereon. 20

The head-bar, head-piece frame, or casing indicated generally by numeral 10 is composed of a main body portion 11 which is substantially U-shaped in cross section (see Fig. 2), and a shiftable member 12 at each end thereof extendible with relation to portion 11. The extensible members 12 are shaped to correspond with the configuration of body portion 11 and to nest therein, being retained in position by means of the screws 13 in threaded engagement with said members. Screws 13 freely penetrate longitudinally directed slots 14 located in the bottom wall of the body portion 11, while the heads of said screws engage the lower surface of said body portion 11. It may thus be seen that when screws 13 are loosened the shiftable members 12 may be moved longitudinally with relation to body portion 11. After members 12 are placed in proper position the screws 13 are tightened thereby fixing said members in place. It is to be noted that this last mentioned adjustment is made only once, at a time when the Venetian blind assembly embodying this invention is installed in a given window casement. 30 35 40 45

The front vertical wall 15 of each of members 12 is preferably coextensive in height with the front wall of body portion 11 thereby promoting a neat appearance of the casing 10 as best seen in Figure 1 of the accompanying drawing. The rear vertical wall 16 of each of members 12 is shown as comparatively reduced in height thereby resulting in a saving in material and weight. It is to be considered however, as being within the scope of this invention to increase the height 50 55

of wall 16 until it is coextensive with the rear wall of the body portion 11, thereby increasing the dust-proof properties of the casing 10.

Each of the members 12 is carried by a bracket 17, by resting upon an inwardly extending flange 18 horizontally bent from said bracket. Flange 18 is continued into a vertically bent portion 19 which serves as a transverse limit or stop. The horizontal portion of said flange 18 is provided with an open ended slot 19 transversely disposed relative to the casing 10. Each of the members 12 is provided with a thumbscrew 20 which freely penetrates slot 19 and is in threaded engagement with said member.

In the installation of this Venetian blind assembly, the brackets 17 are attached to the window casement 21 in any suitable manner as for example by screws (not shown) penetrating the orifices 22 in the brackets 17. The position of members 12 is adjusted relative to the body portion 11 in a manner described above so that the thumbscrews 20 may be inserted into the slots 19. When the members 12 are in the position shown in Figure 3, or fully seated, the thumbscrews 20 are tightened thus locking the casing 10 in place. When the position of members 12 has once been determined, as stated above, removal or replacement of the casing 10 requires only the manipulation of the thumbscrews 20. The outer vertical edge of each wall 15 may be extended to cover a portion of the bracket 17 as shown in Figure 3 or to disclose same as seen in Figure 1.

Numerals 23 and 24 designate operating cords which control any suitable slat tilting and elevating mechanisms as for example those shown, and more particularly described in my co-pending applications bearing Serial Nos. 19,184 (May 1, 1935) and 50,122 (Nov. 16, 1935).

The cords 23 and 24 pass over idler rollers or pulleys 25 which may be single or pairs of independent rollers as desired, and thence downwardly through the casing 10. The body portion 11 is provided with open ended slots 26 in each end of the bottom wall thereof, while the members 12 are suitably orificed as at numeral 27 so that these openings are aligned and the cords 23 and 24 are given unobstructed passage therethrough regardless of the normal displacements of the members 12 as inhibited by screws 13 in slots 14.

The pulleys 25 are mounted upon the members 12 and shift therewith, said mounting being accomplished in any suitable manner but preferably by trunnioning in irregularly shaped inverted U-shaped brackets 28 affixed to members 12 for example by spot welding. The configuration of brackets 28 is illustrated in Figure 2.

From the above description it will be seen that the present invention provides for a Venetian blind which can be manufactured in standard sizes and conveniently adjusted to permit installation in window casements of various widths and that no particular skill is required to do so, while removal and replacement is also a simple matter.

The foregoing disclosure is to be regarded as descriptive and illustrative only, and not as restrictive or limitative of the invention, of which obviously an embodiment may be constructed including modifications without departing from the general scope herein indicated and denoted in the appended claims.

Having thus described my invention, what I claim as new and desire to secure by Letters Patent, is:

1. A Venetian blind head-bar or casing having a vertically disposed projection proximate an end thereof, in combination with a bracket for supporting the end of said head-bar or casing having the projection aforesaid, said bracket including a horizontal flange having a transversely directed open-ended slot for engaging the said projection on the head-bar or casing.

2. A Venetian blind head bar having a perpendicularly disposed projection proximate an end thereof, in combination with a bracket for supporting that end of said head bar having said projection, said bracket including a vertical flange serving as a rear stop for transverse movement of said head bar, and a horizontal flange having a transversely directed open-ended slot for engaging the said projection whereby movement of the head bar is permitted transversely but prevented longitudinally thereof.

3. A Venetian blind head bar having clamping means thereon proximate an end thereof, in combination with a bracket for supporting that end of said head bar having said clamping means, said bracket including a horizontal flange having a transversely directed open-ended slot permitting the entrance therein of said clamping means and whereby actuation of said means results in the detachable connection of the said end of the head bar to said flange.

4. A Venetian blind head bar having clamping means thereon proximate an end thereof, in combination with a bracket for supporting that end of said head bar having said clamping means, said bracket including a vertical flange serving as a rear stop for transverse movement of the head bar, and a transverse horizontal flange having an open ended slot permitting the entrance therein of said clamping means and whereby actuation of said means results in the detachable connection of the said end of the head bar to the horizontal flange.

5. A Venetian blind head bar comprising a member adjustably attached to the head bar proximate one end thereof and a projection on said member, in combination with a bracket for supporting the end of said bar having the member aforesaid, said bracket including a horizontal flange having a transversely directed open ended slot permitting the entrance therein of said projection whereby movement of the head bar is permitted transversely but prevented longitudinally thereof.

6. A Venetian blind head bar comprising a member adjustably attached to the head bar proximate one end thereof and a projection on said member, in combination with a bracket for supporting the end of said bar having the member aforesaid, said bracket including a vertical flange serving as a rear stop for the transverse movement of said head bar, and a horizontal flange having a transversely directed open-ended slot permitting the entrance therein of said projection whereby movement of the head bar is permitted transversely but prevented longitudinally thereof.

7. A Venetian blind head bar comprising a member adjustably attached to the head bar proximate one end thereof and clamping means on said member; in combination with a bracket for supporting the end of said head bar having the member aforesaid, said bracket including a horizontal flange having a transversely directed open ended slot permitting the entrance therein of said clamping means and whereby actuation

of said means results in the detachable connection of the end of said head bar to said flange.

8. A Venetian blind head bar comprising a member adjustably attached to the head bar proximate one end thereof and clamping means on said member; in combination with a bracket for supporting the end of said head bar having the member aforesaid, said bracket including a vertical flange serving as a rear stop for transverse movement of said head bar, and a horizontal flange having a transversely directed open-ended slot permitting the entrance therein of said clamping means and whereby actuation of said means results in the detachable connection of the end of the head bar to the horizontal flange.

9. A Venetian blind head bar comprising a member adjustably attached to the head bar proximate one end thereof and a projection on said member, in combination with a bracket for supporting the end of said bar having the member aforesaid, said bracket including a side portion, a vertical flange serving as a rear stop for the transverse movement of said head bar, and a horizontal flange having a transversely directed open-ended slot permitting the entrance therein of said projection whereby movement of the head bar is permitted transversely but prevented longitudinally thereof.

10. A Venetian blind head bar comprising a member adjustably attached to the head bar proximate one end thereof and clamping means on said member; in combination with a bracket for supporting the end of said bar having the member aforesaid, said bracket including a side portion, and a horizontal flange having a transversely directed open-ended slot permitting the entrance therein of said clamping means and whereby actuation of said means results in the detachable connection of the end of said bar to said flange.

11. A Venetian blind head bar comprising a member adjustably attached to the head bar proximate one end thereof and clamping means on said member; in combination with a bracket for supporting the end of said bar having the member aforesaid, said bracket including a side portion, a vertical flange serving as a rear stop for transverse movement of said bar, and a horizontal flange having a transversely directed open-ended slot permitting the entrance therein of said clamping means whereby actuation of said means results in the detachable connection of the end of said member to the horizontal flange.

JULIUS NISENSON.
